UNITED STATES PATENT OFFICE.

CHARLES W. CRABTREE AND JOHN W. COLLINS, OF KINSTON, NORTH CAROLINA; SAID CRABTREE ASSIGNOR TO HENRY D. HARPER, OF SAME PLACE.

STOVE-DAMPER.

SPECIFICATION forming part of Letters Patent No. 436,697, dated September 16, 1890.

Application filed April 12, 1890. Serial No. 347,658. (No model.)

To all whom it may concern:

Be it known that we, CHARLES W. CRABTREE and JOHN W. COLLINS, citizens of the United States, residing at Kinston, in the county of 5 Lenoir and State of North Carolina, have invented certain new and useful Improvements in Stove-Dampers; and we do hereby declare that the following is a full, clear, and exact description of the same, reference being had to the annexed drawings, making a part of this specification, and to the letters of reference marked thereon.

This invention relates to certain new and useful improvements in dampers for stoves, 15 designed more particularly for cooking-stoves; and it has for its object, among others, to provide for the ready repair or replacement of a damper when from any cause it becomes out of order or broken or worn out. Our 20 damper will not bind, even though the top of the stove settles or warps downward, and, being operated from the outside, can be easily replaced by unskilled labor.

Jointed dampers have been proposed, so that 25 they may be readily replaced without removing the rods of the stove or taking the stove to pieces; but while these dampers can be very readily managed when new, as far as putting in is concerned, when the damper-rod is 30 broken or burned off the rust and fire have so set the nut that it can only be removed by the use of a cold-chisel or analogous device. With inside dampers, when the top of the stove settles or warps, as it is almost sure to 35 do in a short time, the damper will bind, rendering it impossible to operate it without breaking the rod (or handle) or to fit a new damper without trimming the same, so that the stove must be taken to the shop for re- 40 pairs.

Our improvements are designed to overcome these difficulties, to more effectually regulate the temperature of the stove, and to save fuel.

Other objects and advantages of the invention 45 will hereinafter appear, and the novel features thereof will be specifically defined by the appended claims, the novelty residing in the peculiarities of construction and the combinations, arrangement, and adaptation of 50 parts, all as more fully hereinafter described,

shown in the drawings, and then particularly pointed out in the appended claims.

The invention is clearly illustrated in the accompanying drawings, which, with the letters of reference marked thereon, form a part 55 of this specification, and in which—

Figure 1 is a perspective view of a portion of a stove with our improvements applied thereto. Fig. 2 is a vertical section through the same.

Like letters of reference indicate like parts in both views.

Referring now to the details of the drawings by letter, A designates the upper portion of a cooking-stove, through the "main top" 65 B of which is formed an opening C, surrounded by a neck a to receive the smoke-pipe b, (shown by dotted lines,) which neck is known as the "pipe-collar." A short distance in front of the pipe-collar there is formed through the 70 main top an opening, through which the damper is designed to slide. The main top upon each side of this opening on the under side is formed with depending ribs c, which serve both to strengthen the same and also 75 as guides for the damper.

D are the flanges or projecting edges on the "flue-strips" of almost all cooking stoves and ranges, serving to support the damper, as shown in both views, and E is the damper, of 80 any suitable material, adapted to work through the opening and be guided by the said ribs and flanges, as shown. The upper edge of this damper is formed with a head-piece substantially T-shaped in cross-section, as 85 shown, and which is adapted when the damper is down to bridge the opening in the main top and closely cover the same and prevent ingress of air or escape of the smoke, as will be readily understood.

F is a yoke of substantially rectangular form pivoted upon the brackets or posts G on the top of the stove upon opposite sides of the opening C therein, and at the front end this yoke or lever is pivotally connected with the 95 head of the damper in any suitable manner, preferably, however, as shown in the drawings, wherein the head is shown as formed with upwardly-extending lugs d, to which are pivotally connected one end of the links e, 100

the opposite ends of which are pivotally connected to the front bar of the yoke or lever, as shown.

It will readily be seen how by operating the lever the damper may be readily controlled. The upper end of the damper and all the arrangements for working it being at all times within full view of the attendant serves as a reminder that there is a damper to the stove 10 and also as an indicator to tell the amount that the damper is opened.

Of course various modifications in detail may be resorted to without departing from the spirit of the invention. For instance, the 15 head of the damper may be formed with but a single upwardly-extending lug arranged centrally and only one link employed.

We preferably employ thumb-screws as the 20 pivots for the lever, but do not restrict ourselves to their use.

To form the necessary combination with a 25 large number of the stoves and ranges now made, the only alteration necessary would be that in the main top—to wit, the opening to receive the damper and the bolt-holes—one on each side of the pipe-collar—through which to bolt the posts G to the stove, as the damper may slide downward between the front edges of the flue-strips and just back of the flanges 30 on same. It may occasionally occur that a stove or range may be so constructed that the flue-strips may need slight alteration.

What we claim as new is—

1. The combination, with the main top having an opening therein for the damper and 35 formed upon its under side with depending ribs c upon each side of said opening, of the damper adapted to be moved vertically through said opening and formed at its upper end with lugs d, the uprights on the main top, 40 the yoke pivoted in said uprights, and the links pivotally connecting the front bar of the yoke with the lugs of the damper, substantially as shown and described.

2. The combination, with the main top having an opening therein for the damper and 45 formed upon its under side with depending ribs c upon each side of said opening, of the damper adapted to move vertically in said opening between the ribs and having a T- 50 shaped head above the main top to bridge the opening therein, the forked uprights on the main top, the rectangular yoke pivoted between the forks of the uprights and embracing the smoke-pipe, and the links pivotally 55 connected to the T-shaped head of the damper and with the front bar of the yoke, substantially as shown and described.

In testimony that we claim the above we have hereunto subscribed our names in the 60 presence of two witnesses.

CHARLES W. CRABTREE.
JOHN W. COLLINS.
